ACTUATOR FOR DOOR OPENING MECHANISMS

James P. Burke, Poland, Ohio, assignor, by direct and mesne assignments, of one-half to Murray M. Fibus and one-half to Jerome W. Marcus, both of Youngstown, Ohio

Application March 5, 1949, Serial No. 79,898

1 Claim. (Cl. 268—34)

1

This invention relates to automatic door opening mechanisms and more particularly to actuators therefor.

The principal object of the invention is the provision of a manually operable actuator for a door opening mechanism.

A further object of the invention is the provision of actuator means for door opening mechanisms and including tread plates positioned on each side of the door to be controlled.

A still further object of the invention is the provision of an actuator for door opening mechanisms which is of simple and economic construction and which may be installed easily and conveniently in any doorway to control a door therein.

A still further object of the invention is the provision of an actuator for door opening mechanisms having means preventing the accidental opening of the door against a person approaching the door from the wrong side.

The actuator for door opening mechanisms disclosed herein comprises a simple and efficient mechanism incorporating a minimum number of parts and adapted to replace a threshold portion of a door opening, beneath a door hinged in the opening, and provide tread plates extending outwardly in both sides of the door so that a person approaching the door will of necessity step on one of the tread plates which will then operate the door opening mechanism and cause the door to swing inwardly and away from the person approaching the same.

Means is also provided to render the mechanism inoperative in the event a person approaches the door from the direction in which the door opens so that accidental injury from the swinging door is avoided.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a perspective view with parts broken away illustrating a door opening and a door hinge therein having an opening mechanism and an actuator for said mechanism.

Figure 2 is an enlarged cross sectional detail of a portion of the device shown in Figure 1.

Figure 3 is a horizontal section taken on line 3—3 of Figure 2.

Figure 4 is a vertical section taken on line 4—4 of Figure 2.

By referring to the drawings and figure 1 in particular it will be seen that a doorway is illus-

2

trated and defined by a door frame 10 and has a door 11 hinged therein along its edge 12 so that the door 11 will hinge inwardly, away from the point of view as illustrated in Figure 1. The door frame 10 has a housing 13 mounted above the door 11, which housing 13 encloses an air piston and cylinder assembly 14. A crank arm 15 connects the air piston and cylinder assembly 14 with a bracket 16 which in turn is secured to the door 11 so that operation of the air piston and cylinder assembly 14, as by introducing compressed air thereinto through a pipe 17, will cause the door 11 to swing open, away from the point of view as shown in Figure 1 of the drawings.

In order that the mechanism just described may be controlled, a pair of tread plates 18 and 19 are positioned one on each side of the door 11, the tread plate 18 comprising an entrance tread plate and the tread plate 19 comprising an exit tread plate. The tread plates 18 and 19 are positioned over a bottom plate 20 and hinged thereto at their outermost, oppositely disposed ends by means of hinge assemblies 21 and 22. The tread plates 18 and 19 are supported in elevated relation to the bottom plate 20 by means of groups of springs 23 and 24, respectively, two of which are shown in Figure 1 of the drawings.

It will be observed that the respective innermost opposed edges of the tread plates 18 and 19 are slightly spaced with respect to one another so that either plate may be moved vertically without interfering with the other. The tread plate 18 has an arm 25 secured thereto and extending outwardly from one side thereof as shown in Figure 1 and in Figures 2 and 3 of the drawings. The arm 25 has an adjustable extension member 26 secured thereto by fasteners 27, the outermost end of the extension member 26 entering a box-like enclosure 28 which is secured to the door frame 10 as best shown in Figure 1 of the drawings.

The enclosure 28 has a rocking arm 29 pivoted on a pivot pin 30 which in turn is carried on a bracket 31 secured to the bottom of the enclosure 28. The end of the rocking arm 29 lying adjacent the end of the extension member 26 is provided with a sidewardly extending pin 32 engaged beneath the extension member 26 so that downward motion of the tread plate 18 will move the arm 25 and the extension member 26 downwardly and hence move the rocking arm 29 to cause it to pivot on the pivot pin 30 and cause the opposite end thereof to rise upwardly. A slot 33 is formed in the opposite end of the rocking arm 29 and an extension 34 on one end of an L-shaped lever 35 is engaged in the slot 33. The L-shaped lever 35 is pivoted to a boss 36 by a pivot 37 and the opposite arm of the L-shaped lever 35 is pivoted by a pivot 38 to a sideward extension 39 which in turn has a link 40 pivoted to its outermost end.

The link 40 lies beneath the boss 36 and is connected at its opposite end to a pivot pin 41 which in turn is secured to one end of a slide piece 42 which is slidably mounted by fasteners 43 engaging a slot 44 in the slide piece and secured to the bottom of the housing 28.

The slide piece 42 extends out of the housing 28 and beneath the exit tread plate 19 and has an opening 45 therein and a depression 46 formed therein spaced with respect to one another and adapted to be engaged by a locking pin 47 secured to the underside of the exit tread plate 19. It will be observed that the slide piece 42 lies on the bottom plate 20 heretofore referred to.

The housing 28 encloses an air valve 48 in communication with a source of compressed air by way of a pipe 49 and also connected with the pipe 17 heretofore referred to and by means of which compressed air may be delivered from the valve 48 to the air piston and cylinder assembly so that the door 11 may be opened thereby. The valve 48 has a plunger 50 engaged upon a boss 51 formed on the rocking arm 29 so that when the entrance tread plate 18 is moved downwardly as by a person stepping thereon in approaching the door 11, the resulting movement of the rocking arm 29 will move the plunger 50 of the air valve 48 and permit compressed air to flow from the supply source 49 through the pipe 17 to the air piston and cylinder assembly 16 thereby causing the door 11 to be opened. Simultaneously with this action, the innermost end of the rocking arm 29 will move upwardly and cause the L-shaped lever 35 to pivot on the pivot 37 whereby the opposite end of the L-shaped lever 35 will move the boss 39 toward the door 11 or to the left as shown in Figures 1 and 2, which motion will be carried by the link 40 by the slide piece 42 which in turn moves beneath the exit tread plate 19 and to a position where the opening 45 will register beneath the locking pin 47.

A person stepping from the tread plate 18 to the tread plate 19 as in walking through the open doorway will therefore cause the tread plate 19 to move downwardly whereby the locking pin 47 will register with the opening 45 in the slide piece 42 and thus lock the mechanism in position with the valve 48 open. The door will thus remain open until the person passes through the doorway and steps off of the exit tread plate 19 at which time the springs 24 will elevate the exit tread plate 19, disengage the lock pin 47 from the opening 45 in the slide piece 42 and permit the mechanism to return to normal, closing the air valve 48 and permitting the door 11 to be closed by the spring incorporated in the air piston and cylinder assembly 16.

In order that all of the parts of the mechanism will be returned to normal position, a spring 52 is positioned between the housing 28 and one arm of the L-shaped lever 35 and normally biases the mechanism toward normal inoperative position.

It will thus be seen that the mechanism herein disclosed will operate efficiently to open the door upon the same being approached from the entrance side and that the door will be held open until such time as a person passes through the door and steps off the exit side tread plate.

It will be obvious to those skilled in the art that means is desirable for protecting persons accidentally stepping upon the exit tread plate.

at such time as the door actuator is operated by the entrance tread plate so that such a person will not be injured by the door 11 swinging against the person. Such means is provided and comprises the depression 46 in the slide piece 42 heretofore referred to, which in inoperative position is normally located immediately beneath the locking pin 47. Thus, a person stepping upon the exit tread plate 19 will depress the same and cause the locking pin 47 to engage the depression 46 and thereby hold the slide piece 42 in normal inoperative position as the connecting link 40 and the L-shaped lever 35 control the position of the rocking arm 29 which actuates the air valve 48. As long as a person stands on the exit tread plate 19, the device remains inoperative and the door 11 cannot be opened. There is, therefore, no possibility of accidentally injuring a person even though the entrance tread plate 18 is depressed as by a person seeking to pass through the doorway.

It will thus be seen that the several objects of the invention have been met by the device as disclosed and that the mechanism comprises a simple and efficiently formed device which may be readily installed with a minimum of alteration in any conventional doorway for operating a door operating mechanism in connection with a door hinged in the said doorway.

Having thus described my invention, what I claim is:

The combination of a hinged door having an air operated door opening mechanism in connection therewith and a pair of tread plates one positioned on each side of the door and their innermost opposed edges spaced with respect to each other immediately beneath the said door when in closed position, an envelope of resilient material enclosing the said tread plates, an air valve for controlling the said door operating mechanism and positioned adjacent the said tread plates, a rocking arm pivoted adjacent said air valve and one end of the said rocking arm engaging the said air valve, an arm secured to one of the said tread plates and engaged over one end of the said rocking arm for imparting movement thereto whereby the said valve may be actuated, an inverted V-shaped lever pivoted adjacent one end of the said rocking arm and pivoted thereto and a slide piece disposed beneath the other one of the said tread plates and pivoted to the other arm of the said inverted V-shaped lever, a locking pin secured to the last mentioned tread plate and an opening in said slide piece, the said locking pin registering with said opening when the first mentioned tread plate is in depressed position for holding the said air valve open during the progressive depressing of the first mentioned and last mentioned tread plates.

JAMES P. BURKE.
